CLAIM

The ornamental design for a light having a pivotable head, as shown and described.

DESCRIPTION

FIG. 1 is a perspective view of an ornamental design for a light having a pivotable head;

FIG. 2 is a second perspective view thereof;

FIG. 3 is a side view of a first side thereof;

FIG. 4 is a side view of a second side thereof;

FIG. 5 is a side view of a third side thereof;

FIG. 6 is a side view of a fourth side thereof;

FIG. 7 is an end view of a first end thereof;

FIG. 8 is an end view of a second end thereof;

FIG. 9 is a side view of the first side thereof with the pivotable head pivoted upward to an alternate position;

FIG. 10 is a side view of the first side thereof with the pivotable head pivoted further upward to an alternate position;

FIG. 11 is a side view of the first side thereof with the pivotable head pivoted downward to an alternate position;

FIG. 12 is a side view of the first side thereof with the pivotable head pivoted further downward to an alternate position;

FIG. 13 is a first perspective view thereof with a mounting bracket attached; and,

FIG. 14 is a second perspective view thereof with the mounting bracket attached.

Broken lines in the illustrations of the drawing indicate unclaimed parts of the article that form no part of the design illustrated and claimed herein, and are not part of the claimed design. The mounting bracket shown in broken line in FIGS. 13-14 is not part of the claimed design.
